(57) **CLAIM**

The ornamental design for a pin connector with pin and socket type aligners, as shown and described.

DESCRIPTION

FIG. 1 is a perspective view of the pin connector with pin and socket type aligners of my new design.

FIG. 2 is a top plan view of the pin connector with pin and socket type aligners shown in FIG. 1.

FIG. 3 is a bottom plan view of the pin connector with pin and socket type aligners shown in FIG. 1.

FIG. 4 is a front elevational view of the pin connector with pin and socket type aligners shown in FIG. 1.

FIG. 5 is a rear elevational view of the pin connector with pin and socket type aligners shown in FIG. 1.

FIG. 6 is a right side elevational view of the pin connector with pin and socket type aligners shown in FIG. 1; and, FIG. 7 is a left side elevational view of the pin connector with pin and socket type aligners shown in FIG. 1.

The broken lines showing throughout the drawing figures are included for the purpose of illustrating environmental structure only and form no part of the claimed design.
